UNITED STATES PATENT OFFICE

WILLIAM D. COLLINS AND ELMER WIDERBORG, OF EVANSVILLE, INDIANA, ASSIGNEES,
BY MESNE ASSIGNMENTS, TO SERVEL, INC., OF NEW YORK, N. Y., A CORPORATION
OF DELAWARE

SLIDING MOTOR BASE

Application filed April 15, 1926. Serial No. 102,171.

Our invention relates to adjustable mountings for motors and other small units of machinery.

It is an object of our invention to provide a base for a motor which may be readily adjusted so as to shift the motor.

A further object is to provide an adjustable sliding base for motors which is simple in construction, is very rigid and which can be quickly and easily adjusted so as to clamp the motor base in any desired position.

Other objects will appear from the following description, reference being had to the accompanying drawings, in which

15 Figure 1 is a plan view of the sliding base with the motor shown in position in dotted lines;

Figure 2 is an end elevation thereof; and

20 Figure 3 is a side elevation thereof, parts being shown broken away at the vertical plane through the center line of the bolt.

The base plate 4 to which the motor 7 may be bolted has depending flanges 4^a formed at its ends, and rests on two parallel 25 angle irons 5 which form the guides for the base plate and which are suitably secured to the foundation support 6. Each of the flanges 4^a has an L-shaped slot 4^b formed therein near the central portion of the flange.

30 A bolt 8 extends through the suitable holes drilled in the vertical portions of the angle irons 5 and also through the slots 4^b in the depending flanges 4^a. The horizontal portions of the slots 4^b permit the base to be slid

35 on the angle irons 5 to provide for adjustment of the position of the motor or dynamo 7 to properly tension its belt, while the vertical portions permit the ready removal of base plate and motor by raising them from the angle irons, without removing the bolt. This bolt is threaded at its ends to receive the nuts 9 and 10, and a locking plate 12 which is 40 screwed on at the right-hand end (Fig. 3) of the bolt 8. Through the engagement of its 45 pendant portion 12^a with the foundation support 6, the locking plate prevents rotation of the bolt. The bolt passes through a tubular separator or spacing member 11 which fits snugly between the vertical portions of the

50 angle irons 5.

The plate 4 may be readily removed from and replaced on the angle irons 5 by sliding it to the right (Fig. 2) and raising it permitting the bolt to pass through the vertical end of the L-shaped slot 4^b. Upon tightening the 55 nut 10 there will be a frictional clamping action between each of the depending flanges 4^a and its adjacent angle iron 5 due to the interposition of the separator 11, and thus by merely loosening and tightening the one nut, 60 the motor may be shifted and clamped in any desired position.

It will be apparent to those skilled in the art that slight changes, such as cutting the slots in the angle irons instead of in the base 65 flanges, may be made without departure from the principles of our invention. We do not wish to limit our invention to the exact structure disclosed, but what we claim and desire to secure by Letters Patent is:

1. In an adjustable mounting for motors, the combination of a plate having downwardly extending flanges at its opposite sides, each of said flanges having a centrally located open end L-shaped slot, a pair of supporting 75 angles positioned adjacent said flanges, a bolt extending through said angles and the slots in said flanges, a spacing member surrounding said bolt and fitting between the inner surfaces of said angles, and means to prevent rotation of one end of said bolt so that said flanges may be frictionally clamped to their adjacent angle plates by drawing up the nut at the other end of said bolt.

2. An adjustable mounting for machinery, 85 comprising a pair of upwardly extending supporting members, a plate resting upon the upper edges of said members and having downwardly extending flanges adjacent said members, said flanges having similar longitudinal slots therein, a bolt passing through said members and having its ends projecting through said slots, a separator between said members, and means for preventing rotation of said bolt so that both of said flanges may 95 be frictionally clamped to their adjacent members by tightening the nut at one end of said bolt.

3. An adjustable motor base, comprising a 100 base plate to which a motor is adapted to

be secured, said plate having depending flanges at its sides, said flanges having opposed L-shaped slots therein, a pair of guiding and supporting angle irons having vertical surfaces in contact with said flanges, a bolt extending through said angles and said slots in said flanges, a member surrounding said bolt for maintaining said angle irons in spaced relation, and a locking plate secured at one end of said bolt to prevent rotation thereof.

4. In an adjustable mounting for machinery, a base plate, supporting means therefor, said base plate and said supporting means having pairs of respectively juxtaposed flanges, a bolt passing through said flanges, said bolt being held against lateral movement in one pair and laterally slidabie in slots in the other pair of said flanges, a spacing member surrounding said bolt and adapted to separate a pair of said flanges, a locking plate secured to one end of said bolt to prevent rotation thereof so that upon tightening the nut at the other end of said bolt said pairs of flanges may be frictionally clamped together to secure said base plate to said support.

5. An adjustable mounting for machinery comprising a movable base plate individually adapted to support a motor or the like having longitudinally extending lateral bearing surfaces at its outer lateral sides, parallel supporting members having longitudinally extending bearing surfaces adapted to coact with the aforesaid lateral surfaces and a single transversely extending member passing through the base plate and said members adapted to simultaneously clamp said surfaces together.

6. An adjustable mounting for machinery comprising a movable base plate individually adapted to support a motor or the like having longitudinally extending side flanges having lateral bearing surfaces, parallel supporting members having longitudinally extending bearing surfaces adapted to coact with the aforesaid lateral surfaces, a single transversely extending bolting member adapted to simultaneously clamp said surfaces together and a tubular separator surrounding said bolting member and serving to maintain said parallel supporting members in alignment.

In witness whereof, we hereunto subscribe our names this 12th day of April, 1926.
